E. T. Silvius,
ATTORNEY.

UNITED STATES PATENT OFFICE.

JUSTUS H. HENKES, OF VINCENNES, INDIANA.

WATCH-CHARM CHAIN.

Application filed May 16, 1921. Serial No. 470,109.

To all whom it may concern:

Be it known that I, JUSTUS H. HENKES, a citizen of the United States, residing at Vincennes, in the county of Knox and State 5 of Indiana, have invented a new and useful Watch-Charm Chain, of which the following is a specification, reference being had to the accompanying drawings, and to the letters and figures of reference marked 10 thereon.

This invention relates to a watch chain having an emblem link therein, especially a relatively large link on which a society or 15 lodge emblem may be displayed and of sufficiently large size to be easily seen and understood, the invention having reference more particularly to a charm link that is 20 designed to be quickly connected permanently with various styles of link chains that may be designed to be used in connection with watches or be adapted to be used as neck chains.

An object of the invention is to provide 25 an improved watch charm chain that shall be so constructed as to have an emblem that shall permanently remain in a certain position relatively to the different portions of the chain, so that the emblem cannot slip 30 towards either end of the chain.

Another object is to provide a watch 35 charm or emblem chain that shall have an emblem link so connected with the chain that it cannot ordinarily in use turn over on the parts of the chain to which it may be connected, a purpose being to maintain 40 the emblem link with its face and the emblem thereon outward or in plain view.

A further object is to provide an improved emblem link for chains and connecting 45 devices therefor which will permit the emblem link to be quickly and permanently connected with a chain, in order that a purchaser may select a chain according to his fancy and also select any certain emblem 50 and style of emblem link and have the jeweler quickly connect the emblem link to the chain, without necessitating soldering operations, so that the customer need not wait long for the particular charm or emblem chain selected.

With the above-mentioned and other objects in view, the invention consists in an improved charm chain and in an improved emblem link including improved means for 55 quickly and permanently connecting an emblem link to chain links; and the invention

consists also further in the parts and combination and arrangements of parts as hereinafter particularly described and further set forth in the appended claims. 60

Referring to the drawings,—Figure 1 is a fragmentary illustration of a garment on a man and showing one of the numerous ways in which the improved chain may be worn or carried; Fig. 2 is a view of the 65 improved chain, partially broken away, arranged approximately as in Fig. 1 but showing the emblem link in central section or with the front thereof removed; Fig. 3 illustrates the improved chain in which the 70 emblem link is slightly modified and has a different emblem thereon, to adapt a chain to be fastened to a coat with a watch carried in a coat pocket; Fig. 4 is a front view of the improved emblem link in one of its 75 various forms; Fig. 5 is an end view of the link shown in Fig. 4; Fig. 6 is a front view of the emblem link slightly modified; Fig. 7 is a plan of one of the devices whereby 80 the emblem link is securely connected to another link of a chain.

Similar reference characters in the various figures of the drawings indicate corresponding parts or features of construction hereinafter particularly described in detail. 85

In the drawings the numeral 1 indicates a man, 2 a garment such as a vest having pockets 3 and 4, a watch being commonly carried in one pocket and the watch chain secured in the other pocket, so that the 90 watch chain extends from one to the other pocket.

The charm or emblem chain comprises a chain section composed of a suitable number of links 5 and a ring 6 connected to one end 95 of the section, and also another chain section composed of a suitable number of links 7 and a snap link 8 connected to one end of the section. The chain links 5 and 7 may be alike and of any suitable or desired design to afford a variety of styles from which a customer may make a selection irrespective of the type or style of emblem that may be desired. It should be understood that when offered for sale by the jeweler the two 100 sections of the chain may be either separate or connected together, as may have been determined by the manufacturer of the chain. The devices 6 and 8 or the ends of the chain may be variously constructed for the purposes intended so that the chain may be 110 adapted to be used in various ways.

The charm or emblem link as constructed in one form comprises a front plate 9 having a suitable emblem 10 on its face, the plate preferably being approximately oblong and 5 it is connected to a box wall having a top portion 11 and a bottom portion 12 and also two approximately arcuate ends, one end preferably comprising a main portion 13 and relatively angular portions 14 and 10 15 connected with the top and bottom portions respectively, the opposite end comprising a main portion 16 and relatively angular portions 17 and 18 connected to the top and bottom portions respectively. A 15 back plate 19 corresponding in contour to the front plate 9 and the box wall is connected to the box wall, so that there is space between the front and back plates of the link. One end wall has a slot or hole 20 20 which extends partially in the portion 13 and partially in the portion 14, and the opposite end has a slot or hole 21 which is partially in the portion 16 and partially in the portion 17. The emblem link is provided with two devices for connecting it 25 to the chain sections, the devices being originally separate from the emblem link and are designed to be secured to the link when required. The connecting devices are alike 30 but reversely arranged in connection with the emblem link, one device comprising a non-continuous ring or eye 22 having shank members 23 and 24 that extend from opposite sides of the gap in the ring or eye in 35 spaced apart relation so as to permit either member to pass through a chain link, and the shank members have crooks 25 and 26 on their ends from which extend wings 27 and 28 respectively adjacent to the outer 40 sides of the shank members, the wings extending outwardly from the members. The complete device is composed of elastic material, of the character of spring wire. The opposite device comprises a ring 22', shank 45 members 23' and 24' having crooks 25' and 26' and associated wings 27' and 28'. When the devices are finally assembled the shank members 23 and 24 are located in the slot 20 and the shanks 23' and 24' are located in 50 the slot 21, so that the rings shall project from the upper corners of the chain link.

When it is desired to use the charm chain on a coat or an outing shirt or garment a button or pin 29 is provided which has an 55 eye 30 that is connected to the end of one section of the chain, leaving the other section of the chain connected with a watch, as is customary. In such cases the chain hangs from the button or pin and the chain link 60 is slightly modified so as to be centrally suspended and may be shaped so as to have an approximately oval front plate 31 having a desired emblem 32 on its face, also back plate 33, the link having side wall portions 34 and 35 and curved end wall por-

tions 36 and 37, each end wall portion having a slot 38 centrally arranged therein to receive the shank members of the connecting rings.

In some cases the charm link may have a 70 front plate 39 of shield form on which is a suitable emblem 40, the shield contour including corner wall portions 41 and 42 relatively obtuse angled, similar to the wall portions 13 and 14, and opposite corner wall 75 portions 43 and 44 of similar contour, the rings 22 and 22' being connected to such corner portions, so that the major portion of the link shall be pendant when the chain is supported at its ends. 80

In practical use, after a particular style of chain has been selected and a suitable emblem link has also been selected, in case the chain is not divided into two sections, one of the links of the chain is readily cut 85 by a suitable instrument and discarded, after which a ring 22 is connected with a link 5 of the chain section, and the crooks 25 and 26 are entered in the slot in one end of the emblem link and pushed through the 90 slot, the wings 27 and 28 sliding against the ends of the slot and being forced toward the shank members 23 and 24, the shank members being forced together, until the wings have passed through the slot permitting the shank members of the wings to 95 spring apart so that the ends of the wings shall come in contact with the wall portions adjacent to the slot. The companion ring 22' is like-wise connected with a link 7 of 100 the remaining chain section and also with the opposite end of the charm link. The wings are inaccessible from the outside of the link and therefore cannot be drawn back to permit them to pass through the slot, 105 therefore the ring becomes permanently secured in place. The outspread wings in the narrow space between the front and back plates of the link prevent the rings from turning about in the slots or holes, and 110 therefore the emblem link is not likely to turn over so as to obscure its face.

Having thus described the invention, what is claimed as new is—

1. A charm chain emblem link comprising a broad front plate and a broad back plate and also a narrow wall connected to the two plates with a narrow space between the plates, the wall having an aperture therein, a supporting ring provided with a shank extending through the aperture and having elastic securing devices thereon, the devices normally engaging the wall and standing apart a distance greater than the distance between the front and back plates and permanently holding the shank in the aperture and also preventing rotation of the shank in the aperture. 115

2. A charm chain link comprising a wall having two attachment portions, each por- 130

tion being approximately arcuate and having an aperture therein, a broad front plate and a broad back plate connected to the wall with a narrow space between the plates, and two supporting rings having each a shank extending through the apertures respectively, each shank comprising two members having elastic wings thereon respectively that normally engage the inner side of the attachment portion adjacent to the aperture therein and permanently secure the shank in the aperture, the distance from tip to tip of the wings being greater than the distance between the front and back plates.

3. A charm chain comprising two chain sections composed of small links, a relatively large hollow link having a broad front plate and a broad back plate and a narrow wall connected thereto with a nar-

row space between the plates, two portions of the wall having each an aperture therein between the planes of the plates, and two rings having shanks extending through the apertures respectively, each shank having wings thereon engaging the wall portion to permanently secure the shank in place, the distance from tip to tip of the wings being greater than the distance between the plates to prevent rotation of the hollow link on the shank, one of the rings being connected to a link of one of the chain sections, the other of the rings being connected to a link of the remaining one of the chain sections.

In testimony whereof, I affix my signature in presence of two witnesses.

JUSTUS H. HENKES.
